HIGH EFFICIENCY BROADBAND ANTENNA ARRAY

William G. Sterns, Phoenix, Ariz., assignor to Hughes Aircraft Company, Culver City, Calif., a corporation of Delaware

Application December 14, 1954, Serial No. 475,052

10 Claims. (Cl. 343—853)

This invention relates to antenna arrays and more particularly to a system which utilizes R. F. hybrids for achieving a high degree of efficiency in distributing power from a radar transmitter to a radiated lobe in space through an array of radiating elements.

A well-known principle of lobe synthesis is that in which energy is transmitted along a transmission line which has radiating elements so placed along its electrical length, as in a waveguide with spaced slots in one surface, that for a broadside lobe the radiating elements are integral half transmission line wavelengths apart to provide a radiated wave whose phase front is apart to provide a radiated wave whose phase front is parallel to the conductor. For a phase front which is not parallel to the conductor, that is, a beam which is at some direction other than normal to the array of elements, either the frequency of the incident energy or the mechanical spacing of the radiating elements may be changed, such that the elements are no longer separated by exact multiples of the transmission line wavelength of the transmitted energy. The principles involved in such scanning are discussed in U. S. Patents 2,403,729 and 2,409,944 to A. V. Loughren.

In prior art systems the admittance of the array is a critical function of frequency, and control of individual elements is often made difficult by the interaction and interdependence of adjustment of energy coupling to each element. Also, the antenna efficiency of prior art arrays is considerably below the 100% point.

Accordingly, it is an object of this invention to provide a broadband antenna array feed system which is more efficient than prior art systems.

It is another object to provide a highly efficient broadband antenna array feed system in which the input impedance is nearly perfectly matched.

It is a further object to provide a highly efficient antenna array feed system in which exact energy coupling control of the individual elements is achieved with ease and without the difficulties in prior art systems.

Briefly, in accordance with this invention, R. F. power fed to the input of an array impinges upon an R. F. hybrid network where it splits equally into two separate outputs of the hybrid, which are connected through a pair of adjustable irises to a first pair of radiating elements. The irises are adjusted to transmit a predetermined percentage of the power incident thereon and to reflect the remainder back to the hybrid. The transmitted portion is coupled to the radiating elements which are matched to their feed lines. The hybrid recombines the two components of reflected energy into one output. The reflected energy as combined is provided with a predetermined phase delay and then fed to a second hybrid network which, in the same manner as the first hybrid, splits the incident energy into equal components to be fed to a second pair of radiating elements. The second pair of radiating elements also couples to space a predetermined percentage of the energy incident on a second pair of adjustable irises which reflect the remainder back through the second hybrid

functioning in the same manner as the first hybrid. This structure is repeated for as many pairs of radiating elements as are desired, each pair of irises coupling to the radiating elements a certain percentage of the energy incident on the irises. Further, for a uniformly illuminated array, all the radiating elements transmit equal parts of the total energy from the transmitter by virtue of the adjustable irises.

Alternatively, adjustable radiating elements of the character adapted to transmit to space a certain predetermined percentage of the energy incident on each radiating element and to reflect the remainder back into the hybrids and thence on toward subsequent sections of the array may be utilized, thus performing the same lossless reflective function as the irises in the previous embodiment.

The aforementioned phase delays would presumably be predetermined and fixed so as to electrically separate successive radiating elements by an integral number of half wave lengths of the center operating frequency. Then, when the frequency is shifted above or below this center frequency, the lobe will shift from a broadside lobe to a left or right direction. However, the same result may be achieved by using a constant operating frequency and selectively changing the phase delays between radiating elements.

The novel features which are believed to be characteristic of the invention, both as to its organization and method of operation, together with further objects and advantages thereof, will be better understood from the following description considered in connection with the accompanying drawing made a part of this specification. The scope of the invention is pointed out in the claims.

In the drawing Fig. 1 is a schematic diagram of one embodiment of the improved antenna array and feed system of the invention;

Fig. 2 is a frontal view of one arrangement of the radiating elements of the array of Fig. 1;

Fig. 3 is a frontal view of another arrangement of the radiating elements of the array of Fig. 1; and

Fig. 4 is a partial schematic diagram of one section of a second embodiment of the array.

Referring now to the drawing, and particularly to Fig. 1, an input transmission line 10 is connected to one terminal a_1 of an R. F. hybrid network H_1 . Conductor 10 may be a waveguide or coaxial line. The hybrid may be of a type suitable for the operating frequency range to be used. Suitable for microwave frequencies, for example, is the "rat race" type of hybrid; this hybrid is described and discussed in "Microwave Duplexers," MIT Radiation Laboratory Series, volume 14, chapter 8, page 357, by Smullin and Montgomery (McGraw-Hill Book Co., New York, N. Y., 1948) or the Riblet short slot coupler type discussed in the Microwave Development Laboratories, Inc., Quarterly Report, No. 5, 1950, available in the Library of Congress Technical Information Division MICRO-CARD U23169, "Investigation and Development of Broad Band Single Slot Waveguide Hybrid Couplers" by H. J. Riblet. Terminals b_1 and c_1 are the output terminals for energy incident at terminal a_1 and are connected to a radiating element D_1 . Interposed therebetween in each line is an adjustable iris, reflective probe, or other adjustable lossless discontinuity, I_1 . Element D_1 comprises a pair of energy apertures and preferably is matched to the line. Alternatively, D_1 may be of a type which can be adapted to couple to space a predetermined percentage of the energy incident thereon and to reflect the remainder back along the waveguides toward hybrid H_1 , in which case the lossless discontinuities are not used; such a radiating element may be either a dipole pair or a slot pair in a waveguide. Terminal d_1 of hybrid H_1 is the output terminal for energy incident on terminals

b_1 and c_1 after reflection from element D_1 . Terminal d_1 is connected to a phase delay network F_1 , which may be a length of transmission line, any other type of fixed phase delay or a variable phase delay, the actuating means of which may be electrical, as with a solenoid, or may be mechanically coupled to a motor shaft. Actuator 14 is such a device and is coupled to each of the phase delays if the embodiment to be utilized is one which makes use of variable phase delays.

Phase delay network F_1 is also connected to the input terminal a_2 of a hybrid H_2 , which, like hybrid H_1 , has terminals b_2 and c_2 connected to a radiating element D_2 . Again adjustable irises, I_2 , are interposed in the lines between the hybrid and the radiating element. Terminal d_2 is coupled to a phase delay network F_2 , which is of the same structure as phase delay F_1 . Phase delay network F_2 is in turn coupled to input terminal a_3 of a third hybrid H_3 . Terminals b_3 and c_3 of hybrid H_3 are coupled to radiating element D_3 in the same manner; again, adjustable irises, I_3 , are interposed in the lines between the hybrid and the radiating element. Output terminal d_3 of hybrid H_3 is coupled to phase delay network F_3 .

In the same manner the structure of each section of the array is repetitive of the first, second and third sections, as described, for as many sections, 1, 2, 3 . . . n , as are to be included in the array. The energy reflected from the $(n-1)$ th irises is fed through a phase delay network F_{n-1} to the input terminal a_n of hybrid H_n . Terminals b_n and c_n of hybrid H_n are coupled to a radiating element D_n . Output terminal d_n of hybrid H_n is coupled to an absorptive load 12. By matching the element D_n to the transmission line, the amount of energy coupled to the absorptive load 12 can be made negligibly small, thus resulting in very high efficiency. Under these circumstances the load is necessary only for proper operation of the hybrid.

The radiating elements preferably are physically spaced in two dimensions and electrically spaced in one direction. In other words, and as indicated in Figs. 2 and 3, the elements are disposed in the same vertical plane and are parallel to each other. The phase delay networks $F_1, F_2, F_3 \dots F_{n-1}$ are all of the same structure and, if of the electrically controllable type, each is coupled to an actuating device 14. If the phase delay networks are to be actuated mechanically, the actuating device may represent a motor, and the connections to the various phase delay networks would be mechanical. The array shown in the drawing may be only one of a set of radiators going to make up a more complex array.

For purposes of explaining the operation of the invention it will be assumed that a microwave frequency is being transmitted and that waveguides are being used as conductors between the various components. The operation will first be described according to a frequency-shift embodiment in which the phase delay networks $F_1 \dots F_{n-1}$ provide fixed phase delays. The input energy then would be at a varying frequency, centered, for example, about f_0 , at which frequency the radiating elements $D_1 \dots D_n$ are each electrically separated by integral numbers of half wavelengths. Energy incident upon terminal a_1 of hybrid H_1 is equally split into two components which pass out of the hybrid at terminals b_1 and c_1 , respectively, and impinge upon the irises I_1 and I_1' . The irises couple a certain predetermined percentage of the impingement energy to the radiating elements and reflect the remainder back into the hybrid. The percentage coupled to the radiating element D_1 and thence to space is

1th

n

of the total transmitted energy in the case of a uniform array. The remainder is reflected back along the waveguides to terminals b_1 and c_1 . The energy incident upon the hybrid via terminals b_1 and c_1 is recombined into a

single component which leaves at terminal d_1 . This energy then passes along the waveguide to phase delay network F_1 . The length of delay chosen for F_1 is determined by the degree of frequency sensitivity desired to be given to the direction of the lobe. After being delayed by F_1 , the energy passes on to the hybrid H_2 , where again it is split into two components and fed through irises I_2 and I_2' to the second radiating element D_2 which likewise couples to the radiated lobe a certain percentage of the total energy. All the radiating elements $D_1 \dots D_n$ are adapted to radiate an equal amount of energy, but successive ones will necessarily radiate increasingly greater percentages of the energy incident on the respective irises. In like manner, the energy reflected by irises I_2 and I_2' is recombined in hybrid H_2 and sent on to the next fixed phase delay F_2 . In like manner, throughout the array the energy reflected from one pair of irises is recombined, delayed, separated and fed to the next element for as many elements as are desired to be included in the set.

The last of the energy, i. e., that leaving the last phase delay network F_{n-1} , is also separated into two equal components by hybrid H_n and passes on directly to the last radiating element D_n . Any energy reflected therefrom is again recombined in hybrid H_n and passed on to the absorptive load 12, which for the best operation of hybrid H_n is a matched load. Thus it is seen that with the aid of the hybrids, incident energy may vary in frequency causing a lobe to scan without suffering the disadvantages, as discussed before, which are characteristic of prior art systems. It is seen also that with a controllable frequency of incident energy, a controllable direction of lobe may be achieved which need not vary periodically.

If it is desired to use a constant frequency input, scanning may be achieved by changing the phase delay of each of the phase delay components $F_1 \dots F_{n-1}$, and this may be achieved by mechanically coupling actuator 14 to each of the mechanical phase delay networks, or by electrically coupling actuator 14 to each of the electrical phase delay networks as previously indicated. Here again periodic lobe direction may be effected or a controllable lobe direction (not necessarily periodic) may be achieved by controlling actuator 14.

According to the above mentioned alternative embodiment indicated in Fig. 4, which utilizes adjustable radiating elements instead of irises or other lossless discontinuities in the feed lines to the radiating elements, each pair of radiating elements couples to space a different predetermined percentage of the energy incident thereon; and, in the case of a uniform array, each radiates an amount equal to that of each of the others in the array.

Certain R. F. hybrid networks have an inherent 90° phase shift between the output of terminal b and the output of terminal c which would result in an upward bias in the direction of pointing of the radiated lobe (assuming the lobe is being shifted back and forth in a horizontal plane). This may be corrected for, when such a hybrid is to be used, by the interposing of a fixed phase shifter of the order of 90° between terminal c and the respective radiating element in each section of array as indicated in Fig. 4.

What is claimed is:

1. An antenna array system for frequency-shift scanning a predetermined space with a narrow radio frequency beam, said system comprising: 1 through n radiating elements spaced in one dimension where n is any positive integer, each of said radiating elements having a pair of apertures, each of said radiating elements having respective first and second terminals associated respectively with said apertures; 1 through n radio frequency hybrids, each of said hybrids having first, second, third, and fourth terminals, first and second terminals of each radiating element being connected to the first and second terminals of a respective hybrid; 1 through n fixed phase shifters, respective ones of said fixed phase shifters being inter-

posed between said first terminal of respective ones of said hybrids and radiating elements; 1 through $(n-1)$ phase delay networks, the respective third and fourth terminals of successive ones of said hybrids being coupled through respective ones of said phase delay networks; a resistive termination device, said device being coupled to the third terminal of the n th hybrid, and the fourth terminal of the first hybrid being adapted to receive input signals, whereby the fourth terminal of said first hybrid constitutes the input to said array.

2. An antenna array system for frequency-shift scanning a predetermined space with a narrow radio frequency beam, said system comprising: 1 through n radiating elements spaced in one dimension where n is any positive integer, each of said radiating elements having a pair of apertures, each of said radiating elements having respective first and second terminals associated with said apertures; 1 through n radio frequency hybrids, each of said hybrids having first, second, third, and fourth terminals, the first and second terminals of each radiating element being connected to the first and second terminals of a respective hybrid; 1 through n fixed phase shifters, respective ones of said fixed phase shifters being interposed between said first terminal of respective ones of said hybrids and radiating elements; 1 through $(n-1)$ phase delay networks, the respective third and fourth terminals of successive ones of said hybrids being coupled through respective ones of said phase delay networks, said hybrid networks being adapted to separate energy incident upon the fourth terminal into two separate halves obtained at the first and second terminals, and said hybrid networks being also adapted to combine energy incident upon the first and second terminals into one resultant obtained at the third terminal; a resistive termination device, said device being coupled to the third terminal of the n th hybrid, and the fourth terminal of the first hybrid being adapted to receive input signals, whereby the fourth terminal of said first hybrid constitutes the input to said array.

3. An antenna array system as defined in claim 2 including: $n-1$ first lossless discontinuities, each of said first lossless discontinuities being interposed between respective ones of said first terminals of said hybrids and said fixed phase shifter; and $n-1$ second lossless discontinuities, each of said second lossless discontinuities being interposed between respective ones of said second terminals of said hybrids and said second terminals of said radiating elements.

4. An antenna array system for frequency-shift scanning a predetermined space, said system being of the character adapted to couple radio frequency energy to space through a plurality of energy apertures disposed along the electrical length of a conductor, said system comprising: 1 through n radiating elements, where n is any positive integer, electrically spaced in one dimension; 1 through n radio frequency hybrids, each of said hybrids being coupled to a respective radiating element; 1 through $(n-1)$ phase delay networks, said phase delay networks being coupled between successive radio frequency hybrids, each of said hybrid networks being adapted to receive energy and couple it to a radiating element and to couple reflected energy therefrom on toward the n th radiating element; a resistive termination device, said device being coupled to the n th hybrid network and being adapted to absorb energy reflected from the n th radiating element.

5. An antenna array system for frequency-shift scanning a predetermined space with a narrow radar beam, said system comprising: 1 through n radiating elements, where n is any positive integer, electrically spaced in one dimension, each of said radiating elements having a pair of apertures, each of said radiating elements having respective first and second terminals associated with said apertures; 1 through n radio frequency hybrids, each of said hybrids having first, second, third, and fourth terminals; 1 through n fixed phase shifters, said first terminal of each radiating element being connected to said first

terminal of a respective hybrid, said second terminal of each radiating element being coupled through one of said fixed phase shifters to the second terminal of a respective hybrid; 1 through $(n-1)$ phase delay networks, the respective third and fourth terminals of successive hybrids being coupled through respective ones of said phase delay networks, each of said hybrid networks being adapted to separate energy incident upon its fourth terminal into two separate halves obtained at its first and second terminals and to combine energy incident upon the first and second terminals into one resultant obtained at the third terminal; a resistive termination device, said device being coupled to the third terminal of the n th hybrid, and the fourth terminal of the first hybrid being adapted to receive input signals whereby the fourth terminal of said first hybrid constitutes the input to said array system.

6. An antenna array system for scanning a predetermined space with a narrow radar beam, said system comprising: 1 through n radiating elements electrically spaced in one dimension where n is any positive integer; 1 through n radio frequency hybrids, each of said hybrids being coupled to a respective radiating element; 1 through $(n-1)$ variable phase delay networks, said phase delay networks being coupled between successive radio frequency hybrids and being adapted to have a controllable magnitude of delay responsive to an electrical signal, an electrical actuator device, said device being electrically coupled to each of said phase delay networks and being adapted to control in unison thereby the magnitude of phase delay associated with the phase delay networks, each of said hybrid networks being adapted to receive radio frequency energy and couple it to a respective radiating element and to couple reflected energy therefrom on toward the n th radiating element in a manner to provide unidirectional isolation between successive radiating elements; one through n fixed phase shifters, each of said phase shifters being coupled between respective ones of said hybrids and radiating elements; a resistive termination device, said device being coupled to the n th hybrid network and being adapted to absorb energy reflected from the n th radiating element.

7. An antenna array system for scanning a predetermined space with a narrow radar beam, said system being of the character adapted to couple radio frequency energy to space through a plurality of energy apertures disposed along the electrical length of a transmission line, said system comprising: 1 through n radiating elements electrically spaced in one dimension where n is any positive integer; 1 through n radio frequency hybrids, each of said hybrids being coupled to a respective radiating element, each of said hybrid networks being adapted to receive energy and couple it to a radiating element and to couple reflected energy therefrom on towards the n th radiating element in a manner to unidirectionally isolate reflected energy from preceding radiating elements; 1 through n variable phase delay networks; a mechanical actuator device, said device being mechanically coupled to each of said variable phase delay networks and being adapted to control the magnitude of phase delay associated therewith; 60 a resistive termination device, said resistive termination device being coupled to the n th hybrid network and being adapted to absorb energy reflected from the n th radiating element.

8. An antenna array system for scanning a predetermined space with a narrow radio frequency beam, said system comprising: 1 through n radiating elements, where n is any positive integer, electrically spaced in one dimension, each of said radiating elements having a pair of apertures, each of said radiating elements having respective first and second terminals associated with said apertures; 1 through n radio frequency hybrids, each of said hybrids having first, second, third and fourth terminals, the first and second terminals of each radiating element being connected to the first and second terminals of a respective hybrid; 1 through n fixed phase shifters, said

phase shifters being interposed between respective ones of said hybrids and said radiating elements; 1 through $(n-1)$ variable phase delay networks, said variable phase delay networks being adapted to have a controllable magnitude of delay responsive to an electrical signal; an electrical actuator device, said device being electrically coupled to each of said variable phase delay networks and being adapted to control in unison the magnitude of phase delay associated with the variable phase delay networks, each of said hybrid networks being adapted to separate radio frequency energy incident upon the fourth terminal thereof into two separate halves of radio frequency energy obtained at its first and second terminals, and said hybrid networks being also adapted to combine radio frequency energy incident upon said first and second terminals reflected from the respective one of said radiating elements into one resultant obtained at said third terminal; a resistive termination device, said device being coupled to the third terminal of the n th hybrid, and the fourth terminal of the first hybrid being adapted to receive radio frequency input signals whereby the fourth terminal of said first hybrid constitutes the input to said array.

9. An antenna array system for scanning a predetermined space with a narrow radio frequency beam, said system comprising: 1 through n radiating elements electrically spaced in one dimension where n is any positive integer, each of said radiating elements having a pair of apertures, each of said radiating elements having respective first and second terminals associated with said apertures; 1 through n radio frequency hybrids, each of said hybrids having first, second, third and fourth terminals, the first and second terminals of each radiating element being respectively connected to the first and second terminals of a respective hybrid; 1 through n fixed phase shifters, said phase shifters being interposed between the first terminal of respective ones of said hybrids and the first terminal of respective ones of said radiating elements; 1 through $(n-1)$ variable phase delay networks, respective ones of said variable phase delay networks being coupled between the third and the fourth terminals of respective adjacent ones of said hybrids, said variable phase delay networks being adapted to have a controllable magnitude of phase delay responsive to a mechanical action; a mechanical actuator device, said device being mechanically coupled to each of said variable phase delay networks and being adapted to thereby control the mag-

nitude of phase delay associated therewith, said hybrid networks being adapted to separate radio frequency energy incident upon the fourth terminal thereof into two separate halves of radio frequency energy obtained on the first and second terminals thereof, and said hybrid networks being also adapted to combine radio frequency energy incident upon the first and second terminals thereof reflected from the respective one of said radiating elements into one resultant obtained at the third terminal; and a resistive termination device, said device being coupled to the third terminal of the n th hybrid, and the fourth terminal of the first hybrid being adapted to receive radio frequency input signals whereby the fourth terminal of said first hybrid constitutes the input to said array.

10. An antenna array system for frequency-shift scanning a predetermined space with a narrow radio frequency beam, said system comprising: 1 through n radiating elements spaced in one dimension where n is any positive integer, each of said radiating elements having a pair of apertures, each of said radiating elements having respective first and second terminals associated respectively with said apertures; 1 through n radio frequency hybrids, each of said hybrids having first, second, third, and fourth terminals, first and second terminals of each radiating element being connected respectively to the first and second terminals of a respective hybrid; 1 through $2n$ adjustable lossless discontinuities, respective ones of said adjustable lossless discontinuities being interposed between said first and second terminals of respective ones of said hybrids and radiating elements; 1 through $(n-1)$ phase delay networks, the respective third and fourth terminals of successive ones of said hybrids being coupled through respective ones of said phase delay networks; a resistive termination device, said device being coupled to the third terminal of the n th hybrid, and the fourth terminal of the first hybrid being adapted to receive input signals, whereby the fourth terminal of said first hybrid constitutes the input to said array.
